UNITED STATES PATENT OFFICE.

BERTRAM F. BAKER, OF TANNERSVILLE, NEW YORK.

DISPENSING-TUBE BASE.

Application filed January 19, 1927. Serial No. 161,995.

This invention relates to collapsible tube apparatus and has particular reference to supporting means for collapsible dispensing tubes such as are commonly used for ointments, creams, shaving soap, and numerous other well known and popular commodities. The invention has reference generally to that type of devices described and claimed in my co-pending application for dispensing tube holder, Serial No. 142,565, filed October 19th, 1926.

Among the objects of the present improvement is to provide means constituting a base for a collapsible tube which may either be a sealing device for the tube or a separate device applied to a tube already sealed.

A further object of the invention is to provide a supporting member or base for a collapsible tube that is adapted to be sold along with the tube and delivered in the same package or carton.

A still further object of the invention is to provide a supporting base for the collapsible tube or container that will serve as a closure and which may be used repeatedly for successive containers which may be formed of paper or other relatively cheap discardable material.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a perspective view showing a fragment of a collapsible tube having as its base my improved construction.

Fig. 2 is a face view of one of the end pieces.

Fig. 3 is a perspective view of the combined base and end pieces.

Fig. 4 is a modified form of end piece.

Fig. 5 is a face view of another modification of end piece.

Fig. 6 is an assemblage of the cross piece or base and an end piece in accordance with Fig. 5, the cross piece being in section.

Fig. 7 is a sectional detail on the line 7—7 of Fig. 6.

Fig. 8 is a still further modification of end piece.

Figs. 9 and 10 are further modifications indicating the adaptability of my improved base for application to a paper tube or a tube made of cheaper material than metal and with facilities for renewal of the tube in connection with the same base from time to time.

Referring now more specifically to the drawings, I show a tube 15 of any suitable design or construction which after being filled with the commodity to be dispensed has applied to it a channel construction 16 formed preferably of sheet metal and having at each end a pair of wings 17 extending laterally from each other. Each wing is formed with a narrow end 18 adjacent to which are shoulders 19. The narrow end or tongue 18, furthermore, is provided with a lug stamped or pressed therein coincident with the formation of the device. In the form indicated in Fig. 1, the channel member or base 16 may constitute the closing or sealing means for the tube and be applied thereto at the factory so that it constitutes a permanent part of the tube structure. Furthermore, this base member 16 with its wings 17 may in many instances or adaptabilities of use constitute a complete and stable support for the tube, holding the same upright as upon a table or stand. It will be understood, however, that the base 16 may be made as an accessory to the tube and so is adapted to have the normally sealed end of the tube inserted thereinto either directly through the open top slot 20 or endwise through the end slot 21.

It is usually preferable, however, for specially provided end pieces to be used in connection with the wings 17. Such end pieces may assume various designs of construction and especially with numerous details or modifications of means for attachment to the base or cross piece 16. In Figs. 2 and 3 I show a pair of end pieces having a four-sided aspect and each having spokes 22 to one of which is fixed a clip or keeper 23 which surrounds the spoke, and diametrically opposite from the clip 23 is a slidable clip or keeper 24. These end pieces 25 are shown as being duplicates in construction and design. To assemble the cross piece and the end pieces, one wing 17 of each end of the cross bar is slipped into the keeper 23 of the adjacent end piece, the diametrically opposite wing at the same end passing over the slidable keeper 24 at such time and pass-

ing beyond it. The latter keeper being narrower, permits this movement of the wing and thereafter the keeper 24 is moved over the second wing until it comes against the shoulders 19. The parts are then held together frictionally and with the cross bar 16 centered along the axis or constituting the axis of the entire base structure as shown in Fig. 3. The other end piece will be attached in a similar manner. The tube will assume the same position relatively to the cross piece in this assembled construction as is indicated in Fig. 1. As the commodity is discharged gradually from the tube, the tube may be wound or wrapped around the cross piece 16 progressively, insuring that the commodity will be forced from the base end thereof toward the discharge end so that there can be no substantial waste of material as so frequently happens when the pressure upon the tube is made indiscriminately anywhere along its length. Furthermore, while the wrapping of the tube around the cross piece 16 takes place progressively, any one of the four sides of the base may constitute the support for the construction due to the regular or four-sided aspect of the end pieces.

As a cheaper construction Fig. 4 indicates an end piece 25^a in which the clips or keepers are indicated as furnished in flat form at 26 and being made of the same piece of sheet metal such as tin or other easily bendable material. Consequently to apply the end pieces to the wings 17 of the cross bar, the operator simply applies the wings against the spokes 22^a which bear the keepers 26 and then he bends over the ends of the keepers to embrace said wings. This is a very cheap construction and lends itself to the idea of being discarded when the tube is emptied.

In Figs. 5 to 7, each end piece is made in two parts separate from each other and preferably duplicates, and like the form of Fig. 4 is cheaply made of plain sheet metal or its equivalent of uniform thickness. These members shown at 25^b or stamped or formed at their mating edges with interlocking serrations or teeth 27, the teeth of one being received between the teeth of another as shown in Fig. 6, and each member is preferably depressed at 28 so that the teeth of the other will be received in the depressions and present a smooth flat interior surface for the construction. Furthermore, each of the members 25^b has struck from it a tongue or keeper 29, the position of which is set off inward from the main plane of the end piece. To assemble these parts, the two halves of each end piece are brought together from the position of Fig. 5 to that of Fig. 6 in a sort of hinge action and when in the same plane, the wing portion 17 of the cross bar is introduced, the axis of the

two wings being arranged approximately over the joint between the teeth and notches and then swung or turned around the axis of the cross bar 16 as shown by the arrows on Fig. 6, the ends 18 of the wings then gliding into engaging action beneath the keepers 29 where they are held by friction, or by friction in conjunction with a snapping action between lugs 30 formed on the wing extensions 18 and pits 31 similarly formed on the keepers 29. The stiffness of the wing structure of the cross bar serves to hold positively the end pieces in flat and interlocked position and condition. Any tendency for the two parts 25^b of the end piece to separate is resisted by the friction of the materials and especially with the connection therewith of the wings.

In Fig. 8 I show an end piece 25^c in which the two parts are hinged permanently together and the connection therewith of the cross piece is effected as above described. These jointed or hinged end pieces 25^b and 25^c are adapted for close nesting within the same carton as carries the tube and cross piece structure.

In the dispensing of various commodities especially such as condiments including mustard, ketchup, or the like for table use as well as for dispensing commodities as above intimated, there is a growing demand for the substitution of paper or some other sanitary material for the commonly used metal in the construction of a tube. Assuming, therefore, that 15^a represents a paper tube or bag, the dispensing or delivery end of which is not shown herein because it constitutes the subject of a separate application, after the tube or bag is filled with mustard or other commodity to be dispensed, the filling or lower end thereof as indicated at 32 is crimped together and preferably rolled or folded upon itself and introduced into a channel cross member structure 16^a or 16^b of any suitable cross sectional form. In Fig. 9 the cross bar is shown substantially cylindrical and after the end 32 is inserted a round or conical block or wedge 33^a of wood or the like is introduced, making a positive lock as well as seal for the device. In Fig. 10 the crimped and folded end 32^a is merely folded upon itself and the wedge 33^a lies outside of it instead of inside as in Fig. 9. In both cases, however, the closing and sealing of the tube or bag may be done at any time and the same or a fresh bag may be filled or refilled and reinserted into the base structure which in all essentials is the same as above described including the wings 17, extensions 18, and shoulders 19 for co-operation with separable end pieces.

While the mechanism as set forth herein is well adapted for production at low cost and to be discarded whenever the tube that goes with it is emptied, it is obvious that

the construction may be made up of a more permanent nature and of any suitable material such as precious metal, either solid or plated, and so constitute an attractive and useful gift article.

I claim:

1. The herein described base for holding a collapsible tube upright, the same comprising a cross bar, wing extensions extending integrally and angularly from the ends of the cross bar, and a pair of end pieces detachably connected to the wing extensions.

2. A construction as set forth in claim 1 in which the end pieces include keepers having a slip connection with the wing extensions.

3. A base for collapsible tubes comprising a channel cross bar and means co-operating with the cross bar to hold the tube held thereby in erect position, the means co-operating with the cross bar being a pair of end pieces separable from the cross bar, the end pieces each having a plurality of symmetrical sides constituting selective supports.

4. A base for collapsible tubes comprising a channel cross bar and means co-operating with the cross bar to hold the tube held thereby in erect position, the means co-operating with the cross bar to hold the tube being a pair of collapsible end pieces.

5. The herein described base for holding a collapsible tube upright, including a cross bar having oppositely extending wings at the ends thereof, and end pieces at said ends

supporting said cross bar, said end pieces having portions having openings to receive said wings.

6. The herein described base for holding a collapsible tube upright, including a cross bar, end pieces at the ends of said cross bar supporting the same, said end pieces having portions having openings, said cross bar having shouldered members received in said openings.

7. The herein described base for holding a collapsible tube upright, including a cross bar, end pieces at the ends of said bar supporting the same, said bar having opposite extensions at each end piece, said end pieces having each an opening to receive an extension, and a slidably keeper on each end piece engaging the other extension.

8. The herein described base for holding a collapsible tube upright, including a cross member, and detachable supporting means for said member, said means having a portion provided with symmetrical sides constituting selective supports.

9. The herein described base for holding a collapsible tube upright, including a cross member, and supporting means detachably engaging said member, said supporting means being symmetrical and centrally engaging said member to support said tube upright in various relations thereof to said member.

In testimony whereof I affix my signature.

BERTRAM F. BAKER.
